AGITATING DEVICE FOR PHOTOGRAPHIC DEVELOPING BATHS

Carl C. Chambers, Lansdowne, Pa., assignor to
Edward Stern & Company, Incorporated, Philadelphia, Pa., a corporation of Pennsylvania

Application March 26, 1940, Serial No. 326,012

19 Claims.

(Cl. 95—89)

The present invention relates to the treatment of photographic films and plates in developing and fixing baths with particular reference to agitation of baths.

A purpose of the invention is to eliminate the need for cut-and-try operations in the developing of plates and films so that the plates and films may be developed uniformly, reliably and correctly by merely subjecting them to the developing process for a predetermined period of time and preferably as an automatic operation.

A further purpose is to provide a reciprocating agitator of a developing solution with a freedom to accommodate its position to flow reversals of the solution at the end of each stroke of a reciprocator operating the agitator, thereby preventing surges of the treating solution against the developing plate or film of the character which might deflect the plate or film into the path of the agitator and cause scraping or scratching of the plate or film.

A further purpose is, at the end of each stroke, to damp surges in one direction before creating them in the reverse direction.

A further purpose is to avoid sweeping the film or plate frontally back and forth just after the stroke reversals of the agitator.

A further purpose is to avoid or greatly lessen unevenness of agitation at the surface of the developing film or plate and to avoid or greatly lessen standing waves in the solution.

A further purpose is to move a photographic processing bath content across the surface of the film being processed with a component of flow directed transversely toward the film surface in each movement.

Further purposes will appear in the specification and in the claims.

My invention relates both to a new process of agitation of the developing solution for better and more uniform developing conditions at the developing surface of the film or plate and to the agitator for accomplishing my new process.

I have elected to illustrate my invention in a few only of its many forms, selecting forms, however, that are practical and efficient in operation and which well illustrate the principles involved.

Figures 1, 1a and 1b show vertical reciprocations of an agitator element vertically across the vertical face of a film or plate, the views being diagrammatic elevations, showing, in great exaggeration, the intended range of yielding of the agitator with respect to its reciprocator and the views being intended to illustrate some respectively different types of yieldable agitator elements adapted to the present invention.

Figures 1c, 1d and 1e are views corresponding generally to Figures 1, 1a and 1b respectively, except that in each case the yieldable agitator element has been modified for operation simul-

taneously upon two films or plates respectively on opposite sides of the agitator instead of a single film or plate on one side only of the agitator.

5 Figures 2 and 2a are diagrammatic elevations illustrating horizontal reciprocation of a horizontally yieldable agitator element horizontally across the face of a vertical film or plate, the agitator operating respectively on a single film or plate and on two films or plates, and in each case intended for any suitable horizontally yieldable agitator, but showing agitator elements generally like those in Figures 1 and 1c respectively, suitably modified for horizontal instead of vertical reciprocation.

10 Figures 3 and 3a are horizontal sections respectively of Figures 1 and 1c in accord with the section lines 3—3 and 3a—3a thereof taken in the direction of the arrows.

15 Figures 4 and 4a are horizontal sections respectively of Figures 2 and 2a upon the section lines 4—4 and 4a—4a thereof in the direction of the arrows.

20 Figures 5 and 5a are enlarged fragments of Figures 3 and 3a, but with the agitator element in each case in its midposition.

25 Figures 6 and 6a are respectively a bottom plan view of a portion of Figure 2 and a top plan view of a portion of Figure 2a, in each case modified to show the agitator element in its midposition.

30 Figures 7 and 7a are sections respectively of Figures 5 and 5a upon the lines 7—7 and 7a—7a thereof in the direction of the arrows.

35 Figures 8 and 8a are front elevations respectively of Figures 6 and 6a.

40 Figures 9 and 10 are respectively front and side elevations showing a somewhat different type of agitator mount from that in the intended conventional showing of Figure 1.

45 Figures 11 and 12 are front and bottom views of agitator structure, which illustrates that more than one agitator element may be used, spaced from one another on a common reciprocator for relatively large films without need for a correspondingly large reciprocation stroke.

50 Figures 13 and 14 are front views of typical frames to support respectively a photo film and a photo plate when developing.

55 Figure 15 is a top plan of Figure 14.

Like numerals refer to like parts in all figures. Describing in illustration and not in limitation and referring to the drawings:

In the past agitator elements have been reciprocated in front of and across developing photographic films and plates submerged in the developer solution, but in my experience these operations have been only partially satisfactory, since they have been beset with troubles which I find were due to pressure and flow conditions

just after each reversal in the stroke of the agitator.

My studies indicate that in the past there have been unpredictable fluctuant conditions at the plate or film portions near the agitator at the moments immediately following stroke reversals, with sudden condition changes that have brought unevenness in the action of the developer upon the film or plate and with often to-and-fro movements of the developing plate or film such that there has sometimes been a scratching of the developing face of the plate or film against the agitator element.

Particularly in the photo-engraving and photo-offset processes, where very large plates and films are employed, and lack of uniformity of development is likely to be serious when in smaller work it could be ignored, these previous difficulties have completely interfered with automatic processing of films and plates. As a result, it is so far as I know universal to process plates and films for use in photo-engraving and photo-offset printing by the trial and error method under observation of the operator, who determines in each instance when the plate is sufficiently processed.

In the present invention I have corrected these former faults of automatic agitation by making the agitator element free to accommodate its position after each reversal to the existing liquid pressure conditions on opposite sides of the agitator element. In effect, at the end of each stroke, I damp the surgings in one direction before creating surging in the reverse direction, and I do this by providing lost motion between the agitator and the reciprocator carrying the agitator. Stated differently, I make the agitator (preferably right at the blade) yieldable at the beginning of each stroke in a direction counter to that of the beginning stroke and yieldable to the greater frontal liquid pressure to avoid a momentary local turbulence that otherwise would be present, with the unhappy results explained above.

A further feature of considerable importance in the present invention is that in the preferable embodiments of the invention, for example those of Figures 1, 1a, 1c, and 1d, there is a component of liquid flow directed transversely toward the surface of the film or plate during each back and forth movement of the agitator. This component effectively projects the liquid violently against all parts of the plate and against all parts equally.

Thus it will be evident that I obtain back and forth movement of the bath content across the surface of the photographic film or plate being processed, with yielding reversal of the direction of flow of the bath content at the end of each back and forth movement and preferably also with a component of flow directed transversely against the film surface in each back and forth movement. The feature of producing yielding of the flow impulse at the end of each back and forth stroke in a direction counter to the next stroke, and the feature of causing flow transversely toward the film surface during each stroke, I regard as highly important.

Of course, it will be understood that the angle of inclination of the agitator blade toward the film surface may be variant to produce the desired transversely directed flow component, and, in fact, the various figures illustrate variant angles of inclination for the different agitators.

The effect of application of the principles of the present invention to development of photo-

graphic films and plates for use in producing plates in the photo-offset process, particularly the fine screen photo-sensitive gelatine process, has been very pronounced.

By the agitation process of the present invention, it is possible to process entirely on a time basis, producing uniform development over large films and plates and reproduceable for different films and plates, without the necessity of inspection of the films and plates during processing to determine the end point of development. This result has, to the best of my knowledge, never before been attained.

In Figure 1 a photographic film or plate 19 is submerged in developer solution 20 within a container 21, the film or plate 19 being supported in any suitable way, vertical and near one side 22 of the container 21.

An agitator 23 adapted vertically to reciprocate in front of the plate 19 is carried by a reciprocator 24 that is shown as a downward extension from a vertically reciprocatory head 25. The exposed surface of the film or plate faces toward the agitator.

The stroke of the agitator at its edge 26 presented toward the plate 19 is preferably somewhat greater than the vertical extension of the plate, with the agitator on its highest position thus somewhat higher than the top of the film or plate 19 and in its lowest position somewhat lower than the bottom of the film or plate 19. The depth of immersion of the agitator in its high position preferably should be great enough to avoid material surface waves and turbulence at the end of up strokes—as surface turbulence of the developing solution seems to result in a more rapid deterioration of the developer solution than is otherwise present.

The agitator 23 is intended to be adapted to yield with respect to the reciprocator at the beginning of each stroke in a direction counter to that of the beginning stroke and to an extent great enough to relieve a momentary turbulence and mounting of the liquid pressure ahead of the agitator 23 at the start of the new stroke. Such turbulence and mounting liquid pressure in the past have brought both fluctuant movement of the film or plate 19 and an unevenness of development, as between the upper and lower portions of the film or plate receiving the turbulence at the beginning of the strokes and the intermediate portions of the film or plate.

The agitator 23 preferably should be somewhat longer than the horizontal extension (herein called length) of the film or plate 19, at each side the agitator extending some little distance beyond the film or plate (see Figure 3) and being somewhat shorter than the corresponding dimension of the container 21. The face area of the agitator 23 thus will desirably comprise a major portion of the horizontal sectional area of the container.

The numeral 27 is intended to indicate a fragment of any suitable hanger adapted to support the film or plate 19.

The description thus far is intended to apply to each of Figures 1, 1a and 1b, and also to each of Figures 1c, 1d and 1e except that in the latter figures two films or plates are developing at once, with the agitator operating at the two films or plates, one at each of opposite sides of the container, while in each of the former Figures 1, 1a and 1b a single film or plate is developing.

In each of Figures 1, 1a and 1b the film or

plate 19 is near one of the opposite walls of the container, with the reciprocator 24 near the other wall, supporting the agitator 23 near one side; and in each of Figures 1c, 1d and 1e the reciprocator 24' supports the double acting agitator 23' near the middle.

The description also applies to Figures 2 and 2a except that in the latter figures the agitation is horizontal instead of vertical. The agitator 23², being vertical instead of horizontal, is carried on a vertical rod 24², extending downward from a reciprocator head 25² intended to reciprocate horizontally in a direction transverse to the plane of the paper.

Figures 1, 1a and 1b illustrate respectively different types of agitator elements 23, each mounted on a vertical reciprocator 24 and at the beginning of each stroke adapted to yield somewhat in direction counter to that of the new stroke.

In Figure 1, as seen in Figures 3, 5, and 7, the agitator 23 comprises a light preferably metallic sheet recessed at 28 to receive the tubular reciprocator 24 and formed to pivot on a rod 29 through the agitator 23.

The sheet is additionally cut away somewhat at 30 in front of the tubular reciprocator 24 to provide the agitator 23 with a short range of free movement on its pivot 29, the agitator 23 stopping when moved up or down, by its engagement at 29 with the reciprocator 24.

In Figures 1c, 3a, and 5a the double agitator 23' consists of hinge members of light sheet material, hinging on a common rod or pintle 29 through the tubular agitator 24'.

In each of Figures 1a and 1d the agitator 23 or 23' comprises a light resilient sheet fastened at one side or middle respectively to the reciprocator 24 or 24' that is intended to be shown as a sheet optionally of the same length as the agitator. The weight and dimensions of the agitator 23 or 23' are so selected that the sheet will yield to relieve pressure differences above and below the sheet, differences that would be significant at the beginning of each stroke were it not that the agitator 23 or 23' relieves them by yielding in direction counter to that of the new stroke. In this form, the agitator may consist of a very light metallic sheet, or soft rubber or synthetic rubber, for example.

In Figures 1b and 1e the agitator 23 or 23' is in each case intended to be a rectangular plate or sheet having a lost motion slide support at the lower end of the reciprocator 24 or 24'. Each reciprocator 24 or 24' comprises a pair of rods, spaced from one another in a direction transverse to the plane of the paper, so that one rod only is seen in the drawings. A two rod lost motion support of the agitator 23 or 23', as distinguished from a one rod support thereof, prevents angular movement of the agitator, keeping it with its outer edge 26 or outer edges 26 parallel to the film or plate or films or plates.

In the structure of Figures 2, 4, 6, and 8 the vertical rod 24² from the reciprocator head 25² loosely pivots the agitator 23². The agitator 23² is shown as a sheet having one side wrapping the rod 24² above the right bend 31 at the bottom end of the rod. The sheet wrapping is upwardly recessed at 28² to receive the rod bend 31, the bend 31 limiting angular movement of the agitator by its engagements with the rod, on one side by the flat of the sheet and on the other side by the cut edge of the recess.

In Figures 2a, 4a, 6a, and 8a the vertical rod 75

24² down from the horizontal reciprocator head 25² forms in effect a pintle pin for the vertical sheet agitators 23² and the angular movements of the agitators are limited by a cap 32 on the lower end of the rod. The cap 32 is recessed at 33 and 33' to receive the lower edges of the hinging sheets, the edges at 33 or 33' on opposite sides of each sheet 23² limiting the hinge movement of the sheet.

10 The reciprocator 24 or 24' intended to be indicated conventionally in Figures 1 and 1c, but shown as a single tubular member mounting the agitator or agitators at the middle, may be, in fact, for example, parallel arms 24³ at opposite ends of the agitator (Figures 9 and 10).

As illustrated in Figures 9 and 10 the reciprocator 24³ comprises an inverted U bent strip, fastened at 35 to the vertically reciprocator head 25 and with the arms 24³ at their lower ends pivoting opposite ends of the agitator 23.

20 The ends of the agitator 23 are shown cut away to receive the reciprocator arms and to provide edges at 36 to limit the angular movement of the agitator by their upward and downward engagements with the reciprocator arms.

25 Figures 11 and 12 illustrate that the reciprocator 24 may carry more than one agitator 23. As illustrated similar upper and lower agitators are mounted on a common tubular reciprocator 24 by pivot pins 29 and for greater strength the ends of each of the pivot pins are pivotally supported by a horizontal bracket 37 intended to be welded at 38 to the back of the reciprocator. The use of more than one agitator 23 along the agitator stroke is sometimes desirable in that it lessens the requisite length of stroke.

30 Figure 13 illustrates a conventional frame support for a photographic film, with the film 19 shown in dot-and-dash outline.

35 The film 19 is held at the upper and lower corners by clips 40 and 41, the bottom clips 41 being welded at 42 to the bottom of the frame while the upper clips 40 are carried by the ends of a spring 43 that is welded or otherwise fastened at 44 to a cross arm 45 of the framework. The upwardly extending side arms 46 are rigidly fastened to an intermediate portion of the top member 27 which is long enough to span the end walls of the container 21. Downward lugs 47 from the top member are positioned to centrally register the film with respect to the container 21.

40 Figures 14 and 15 show a conventional support for a photographic plate 19. The plate 19, shown outlined in dot-and-dash, fits in an upwardly open U groove 48 of the channel frame structure. The channel structure is fastened at the top to a cross member 27 dimensioned to rest across the walls of the container 21 and provided with downward lugs 47 for properly registering the support, and, therefore, the plate 21 carried by it, with respect to the container 21 of developer solution.

45 It will be evident that while the invention is particularly applicable to the processing of films and plates to be employed in producing photo-engraving or photo-offset plates, especially for color work, the invention is by no means limited to this field, and has application generally in the photographic developing field for processing still pictures and moving picture film.

50 To simplify the references to the photographic material under process, it is described in the claims as film, regardless of whether in fact it is stiff or resilient, and whether, therefore, it would be generally known as a film or a plate.

55 In view of my invention and disclosure varia-

tions and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:

1. In a photographic bath agitation device, including means for supporting a submerged film out of contact with agitating structure, the combination of an agitator of blade form, means for reciprocating the agitator across the surface of a film in a direction parallel to the surface, and means whereby the agitator yields under the action of liquid flow at the end of each reciprocation.

2. In a photographic bath agitation device, including means for supporting a submerged film out of contact with agitating structure, the combination of an agitator of blade form, a reciprocator moving longitudinally of the surface of a film being processed, pivotal means whereby the agitator is reversibly supported on the reciprocator with the agitator inclined toward the film on each reciprocation, and limiting means for the agitator to restrict its angle of inclination.

3. In a device for processing a photographic film, while the film is supported vertical and submerged in a processing solution within a container, an agitator adapted to be reciprocated transversely across the submerged film, a reciprocator for the agitator operatively connected thereto, maintaining the agitator at all times out of contact with the film, and means whereby at the beginning of each reciprocator stroke the agitator is yieldable with respect to the reciprocator in a direction counter to that of the beginning stroke and to the greater pressure of the liquid in front of the agitator.

4. The structure of claim 3 in which the reciprocation strokes of the agitator at the portion thereof near the film are effectively as great as the width of the film.

5. The structure of claim 3 and in which the reciprocation strokes of the agitator are effectively greater than the width of the film.

6. The structure of claim 3 and in which the length of the agitator is at least as great as that of the film.

7. The structure of claim 3 in which the length of the agitator is as great as that of the film and the reciprocation strokes at the portion of the agitator near the film are effectively as great as the width of the film.

8. The structure of claim 3 and in which the reciprocation strokes are effectively vertical.

9. The structure of claim 3 and in which the reciprocation strokes are effectively horizontal.

10. The structure of claim 3 and in which the broadside area of the agitator comprises a major

portion of the area of the processing solution in a direction transverse to the direction of the reciprocation strokes.

11. The structure of claim 3 and in which the agitator is a flap having pivot connection with the reciprocator at the flap side further from the film, in combination with means limiting the hinge movement of the flap.

12. The structure of claim 3 and in which the agitator is a flexible sheet having a free side toward the film and the other side attached to the reciprocator.

13. The structure of claim 3 and in which the agitator has a lost motion slide connection with the reciprocator.

14. The structure of claim 3 and in which the reciprocator comprises a tube to be reciprocated longitudinally, the agitator intermediate its length having pivot support on the tube, with the agitator and its pivot both transverse to the tube length, and with the pivotal movement of the agitator limited by its engagements with the tube.

15. The structure of claim 3 and in which the reciprocator comprises a tube to be reciprocated longitudinally, the agitator intermediate its length having pivot support on the tube transverse to the tube near the middle thereof, having pivots at the agitator ends and a supporting connection between the end pivots and the back of the tube.

16. In a device for processing photographic film while it is in vertical position and submerged in a processing solution within a container, operating simultaneously upon two films, one toward each of opposite sides of the container, an agitator transversely across and between the submerged films, a reciprocator operatively connected to the agitator at a portion thereof intermediate the agitator portions near the opposite films, maintaining the agitator at all times out of contact with the films, and means whereby at the beginning of each reciprocator stroke the agitator portions toward the films are yieldable with respect to the reciprocator in a direction counter to that of the beginning stroke and to accommodate the greater pressure of liquid in front of the agitator.

17. The structure of claim 16 and in which the agitator comprises flaps hinging to opposite sides of the reciprocator with a limited range of hinging movement.

18. The structure of claim 16 and in which the agitator comprises a flexible sheet intermediate fastened to the reciprocator and with free opposite edges presented toward the opposing films.

19. The structure of claim 16 and in which the agitator comprises a plate having an intermediate limited slide connection with the reciprocator and with its opposite edges toward the opposing films.

CARL C. CHAMBERS.
